UNITED STATES PATENT OFFICE.

ALBERT DE LASKI, OF BOSTON, MASSACHUSETTS.

CIRCULAR LOOM.

SPECIFICATION forming part of Letters Patent No. 361,994, dated April 26, 1887.

Application filed September 30, 1886. Serial No. 214,950. (No model.)

To all whom it may concern:

Be it known that I, ALBERT DE LASKI, of Boston, in the county of Suffolk and State of Massachusetts, have invented certain new and useful Improvements in Circular Looms, of which the following is a specification.

My invention relates to looms of the circular type designed to weave a tubular fabric, and particularly such fabrics as are designed 10 for the manufacture of hose for fire-engine or other water-carrying service, gas or steam service, or analogous use.

It is the special purpose of my invention to so improve the organization of looms of the 15 class mentioned as to secure simplicity of construction, steadiness, smoothness, and regularity of motion, strength of the various parts, and convenience and certainty of operation, all to the end that a strong and closely-woven 20 hose-tube or analogous fabric may be rapidly and cheaply woven.

In carrying out the objects of my invention I have substantially reorganized the loom throughout, and I will now proceed to so describe 25 my improvements that others skilled in the art may be able to make and use the same, reference being had to the accompanying drawings, and to the letters of reference marked thereon, forming a part of this specification, the invention being particularly 30 pointed out and distinctly claimed at the end of the explanation of its construction and operation.

Of the drawings, Figure 1 represents a vertical section through the central portion and one side of the loom, said section being taken, as it were, on the line 1 1, Fig. 3, looking in the direction of the arrows, the shuttles, shuttle-drivers, and some of the parts connected 35 therewith being removed and the take-up mechanism being shown in elevation. Fig. 2 is a vertical sectional view through that portion of the machine not shown in Fig. 1. Fig. 3 represents a top plan view of the upper portion of the machine, parts being shown as broken away. Fig. 4 represents a top plan view, parts being broken away, of what I term 40 the "spider-plate," providing bearings and guideways for the slide-blocks, by which the heddle-operating arms are actuated. Fig. 5 represents a vertical section through the up-

per central portion of the parts pictured in Fig. 3, showing more particularly the manner of supporting the spider-plate and slide-actuating cam-plate and their adjuncts. Fig. 6 is 55 a vertical sectional detail view through the means immediately connected with the heddles for actuating the same, and showing also the relationship of the spools and warp-threads to the heddles and the devices for initiating 60 the operation of the stop-motion mechanism in the event of the breaking or failure of a warp-thread. Fig. 7 is a front elevation of a "section" of heddles, their supporting and guiding means, and parts immediately connected therewith for operating the same, a portion of the frame being shown as broken away. Fig. 8 is a sectional detail view illustrating what I term the "shuttle-driving mechanism" as viewed from above. Fig. 9 is a side 70 view of the mechanism shown in Fig. 8. Fig. 10 is a top plan view of a shuttle and its immediately-associated parts pictured as in operative position in the machine, the weaving-pin being represented in section. Fig. 11 is 75 a sectional view through the spreader on the line x x, Fig. 10. Fig. 12 is a front elevation of the shuttle and shuttle-driver and their immediately-associated parts, comprising, substantially, what is represented in Figs. 8 and 80 10 in their proper relative positions when in operation. Fig. 13 is a front view of the shuttle. Fig. 14 is a view of the shuttle viewed from that side in the direction in which it moves when in operation. Fig. 15 is a detail view of 85 certain of the warp-tension devices, hereinafter referred to. Fig. 15^a is a detail view of a modification. Fig. 16 is a vertical sectional view on the line 3 3, Fig. 15. Fig. 17 represents a view similar to Fig. 14, showing a modified (and in 90 some instances preferred) form of means for regulating the tension on the filling-thread drawn from the shuttle-bobbin. Fig. 18 represents, on an enlarged scale, a sectional detail view of a portion of the stop-motion mechanism. Fig. 19 is a vertical sectional view through a portion of the parts shown in Fig. 18 and hereinafter explained. Fig. 20 is a horizontal sectional view on the line 4 4, Fig. 18, showing the parts as in locked position. Fig. 21 is a view similar to that of Fig. 20, 100 showing the parts as in unlocked position.

Fig. 22 is a detail view of the clutch mechanism as viewed from above, some parts being represented in section. Figs. 23 and 24 are views of the west or filling stop-motion mechanism, hereinafter particularly described. Fig. 25 is a detail view, in side elevation, of the fabric-take-up mechanism.

Similar letters of reference indicate similar parts in all of the views.

10 In describing the construction of my organized circular loom, I will begin at the source of power and explain the nature and relationship of the various groups of mechanism, at the same time setting forth their operation and 15 co-operation with connecting parts, following the same through to the point of completing a web and discharging it from the machine, making particular reference to particular figures when necessary to facilitate an understanding of the case.

A represents the base-plate of the frame of the machine, comprising a suitable number of pillars, a, arranged on the line of a circle and secured to the base-plate, which pillars are 25 aided in being firmly sustained in vertical position by braces a'.

a² indicates the supporting-frame, carrying all of the parts directly concerned in the production of a web, which supporting-frame rests 30 upon and is bolted to the upper ends of pillars a, and has directly secured thereto the brackets a³, for supporting the shuttle-track, brackets a⁴, for the heddle-guiding devices, brackets a⁵, for supporting certain portions of 35 the stop-motion mechanism and warp-thread-guiding means, brackets a⁶, for the warp-spoles and warp-tension means, and upper frame-plate, a⁷, for supporting other parts of the loom, as hereinafter explained.

40 B indicates the driving-shaft supported in suitable bearings provided in the bearings or supports b b, to which driving-shaft is rigidly affixed the pulley b', to be driven by the main belt, while the pulley b², to receive the belt 45 connecting it with the pulley b³ on the main shaft b⁴, is loose upon the main shaft B, so as to be longitudinally movable thereon, and is provided with a clutch part, as hereinafter explained.

50 Main shaft b⁴ is arranged longitudinally in bearings in the upper part of the frame, and is provided on its inner end with a bevel-gear, c, constructed and arranged to intermesh with and drive bevel-gear c', provided with a downwardly-extending hub or sleeve, by which it is secured to a sleeve, c², adapted to turn or be rotated on a sleeve, c³, rigidly sustained by its upper end in the machine by a bracket, c⁴, so that as main shaft b⁴ is rotated it will, 55 through the medium of bevel-wheels c c', revolve or actuate all of the parts connected with sleeve c².

D indicates the spools carrying the warp-threads, which spools are arranged to turn in suitable bearings formed in the brackets a⁶. The warp-threads W are conducted from the spools D through eyes d in tension and guide

bar d', secured to arms of brackets a⁶ around tension-drum d², secured at its ends to a rod, d¹², which rod is adapted to turn in suitable 70 bearings formed in said arms of said brackets, (see particularly Figs. 15 and 16,) whence the warp-threads pass through the eyes of feeler-pins d³, connected with the stop-motion mechanism, through the eyes of the heddles 75 d⁴ to the point on the weaving-pin d⁵ where they are woven into the fabric.

By reference to Fig. 15 it will be seen that guide and tension bar d' may be so adjusted in its bearings or supports by means of nuts 23 80 as to vary the angle that the warp-threads may have through the eyes d' with reference to the line of draft between the spools and said guide-eyes and drum d², this construction being for the purpose of adjusting the tension on the 85 warps so as to insure the turning of said drum as they are drawn off. If the warps are light and the goods not very closely woven, the bar d' may be so adjusted as to have the guide-eyes d², as nearly as may be, on a line with the 90 draft of the warps, and vice versa, in case the warps are coarse and laid up with wefts under heavy tension.

In the example shown the tension-bar d' is provided with thirty-four guide-eyes, d, so 95 that that number of warps may be led from the warp-spoles therethrough; or a greater number of eyes may be provided for a greater number of warps, or the use of some dispensed with when a less number of warps is used, as 100 the size or character of the fabric to be woven may demand; and where the tube to be produced is small, and but comparatively few warps are used to each warp-tension mechanism, a grooved wheel or pulley, d¹⁰, may be 105 provided, instead of the drum d², for each warp-thread, which wheel or pulley may be secured to rod d¹², as represented in detail in Fig. 15^a.

E represents the octagonally shaped spider-plate, supported on brackets e, extending up 110 from the circular top plate, a⁷. Said spider-plate is provided in its center with an aperture, e', through which the sleeves c² c³ extend, so as not to come in frictional contact therewith. The spider-plate is provided in its upper face with radial grooves e², to serve as guideways for the sliding blocks e³. (Shown most clearly in Fig. 5.) Said slide-blocks are provided with upwardly-projecting studs e⁴, 120 to which are secured so as to turn thereon anti-friction rollers or bowls e⁵, which rollers or bowls extend into a cam-groove formed in the lower face of a cam-plate, e⁶, rigidly secured to and so as to turn with sleeve c². 125

It will be noticed that the relative arrangement of the spider-plate E and the cam-plate e⁶ is such that the said cam-plate will readily reciprocate the slides in the grooves of the spider-plate, but will at all times positively 130 hold and maintain said slides properly within the grooves. Such a construction secures positiveness and certainty of operation, and presents a compact and durable arrangement.

F represents arms pivoted at one end to slide-blocks e^3 and at their other ends to the outer or upper ends of arms f, rigidly secured at their lower or opposite ends to a rock-shaft, 5 f', adapted to turn in suitable bearings formed in the upper ends of pillars f^2 , extending up from upper circular plate, a^1 , Fig. 6. Rock-shaft f' has an arm, f^3 , rigidly secured thereto at each of its ends, and to each end of each 10 arm f^3 is pivoted one end of rods f^4 , which latter are in like manner connected at their opposite ends with short sleeves or collars f^5 , adapted to slide on rods f^6 , and connected with the heddle-bars f^7 , Figs. 6 and 7. Arm 15 f^3 is connected at substantially its center with rock-shaft f', so that as said shaft is rocked by the movement in and out of slide-blocks e^3 , acting upon arms F f, said arm f^3 will be oscillated and alternately raise and lower the different sets of heddles, 104, with which the opposite ends of arm f^3 are connected, so as to 20 form the shed in the warps for the passage of the shuttle.

The construction whereby I am enabled to 25 operate the heddles, particularly with respect to the radially-grooved spider-plate E, slide-blocks e^3 , and cam-plate e^6 , and their features and adjuncts, I regard as an important feature of the invention.

30 By reference to Fig. 3 it will be seen that of the eight sets of heddles represented but two sets (one on each side of the machine) are in course of operation, while the other six sets (three on one side and three on the opposite side) are at the extreme limit of their movements—three in one extreme position and three in the other—so that the shed will be entirely open at these opposite points, fully enabling a shuttle and other weft-laying devices to operate 35 at each of these points and the position of the warps to be changed therebetween. To place the warp-threads W under the requisite tension, and to keep the latter uniform in degree under all circumstances, I pivot or otherwise 40 fulcrum an arm, G, on the upper circular plate, a^1 , one such arm for each spool D, and provide the outer free end of said arm with a pad, g, adapted to rest on the yarn or thread wound on the spool. A short rod, g' , projecting up 45 from circular plate a^1 , extends through the rear or inner end of arm G, and is provided on its upper end with a nut, g^2 . A spiral spring, g^3 , is interposed between the inner end of arm G and plate a^1 , in such relation thereto as to operate to press said end of said 50 arm upward, and as a consequence the pad g upon the yarn or thread upon the spool D. As is well known, and for reasons so well understood as not to be necessary to be here explained, it requires less force or power to draw 55 yarn off from a full bobbin offering any resistance to such operation than a nearly empty one; and it is in like way well understood that a spiral spring, such as is indicated by g^3 , will 60 act with greater force when closely compressed than when expanded to nearly its utmost limit. It therefore follows from the construc-

tion and arrangement of parts shown that when the spool D is full and spring g^3 is closely compressed it will press pad g upon 70 the yarn with quite its utmost force, and that as the spool becomes empty spring g^3 will become relaxed and press the pad with lighter force upon the yarn or thread, thus making the power necessary to draw the thread or 75 yarn from the spool equal at all times.

The tension exerted on the yarn by the means just described cannot advantageously be made sufficient for successfully weaving such goods as my loom is particularly designed to 80 produce. To provide further tension on the warp-yarns, the tension-drum d^2 , around which said yarns are wound one or more times after passing through the eyes d of guide-bar d^1 , is provided with a band-wheel, g^4 , as shown most 85 clearly in Figs. 1, 15, and 16. A cord or band, g^5 , having one end secured to an extension, g^6 , of the bracket supporting the tension-drum d^2 , is wound around said band-wheel g^4 , and has its other end secured to a short rod, g^7 , extending 90 up through a hole in a plate or bracket on the upper end of bracket d^1 . A thumb-nut, g^8 , is screwed on the lower end of said rod g^7 , so as to regulate the force with which the band g^5 is drawn around wheel g^4 , and as a result 95 effect the force required to draw the yarn wound around the tension-drum d^2 from the spool D, said band g^5 operating with frictional effect on wheel g^4 .

Rigidly secured to a sleeve, H, loosely surrounding revolving sleeve c^2 , is a bevel gear-wheel, h. As said sleeve is connected by brackets h' , or in any other suitable manner, with the stationary parts of the frame, said wheel h is also held stationary. Below the hub of 105 wheel h, and between it and a collar, h^2 , fixed on stationary sleeve c^2 , is a rim or collar, h^3 , secured to revolving sleeve c^2 so as to turn therewith. Said collar h^3 is provided with short arms or extensions h^4 , to which are secured by 110 means of bolts and screws, or in any other suitable manner, the brackets I, carrying what I term the "shuttle-driving mechanism." A shaft, i, journaled in suitable bearings in said bracket I, is provided on its inner end with a 115 bevel-pinion, i', constructed and arranged to mesh with bevel-gear h, and at its opposite end said shaft i is provided with a gear-wheel, i², meshing with a similar gear, i³, fixed on a short shaft, i⁴, having bearings formed in laterally-extending arms i⁵ of bracket I, as seen 120 in Figs. 8 and 12. A smooth or friction faced driving-wheel, i⁶, is also secured to shaft i⁴, just inside of the point at which wheel i³ is secured thereto, the function of which latter 125 wheel will be presently explained. It will now be seen that as sleeve c^2 is revolved, collar h^3 and bracket I, connected therewith, will be carried around with it, and shaft i will be 130 revolved by reason of the engagement of its attached bevel-pinion i' with fixed gear h, and as a consequence driving-wheel i⁶ will be also revolved through the medium of gears i² i³.

The arrangement of shuttle-driving frames

and shuttle-driving devices, as above explained, insures a compact and simple arrangement of the parts, since the shuttle-driving frame is supported directly at the center of the machine 5 in a convenient position for effective operation.

J represents the shuttle, by which term, in its general sense, it is meant to include, substantially, all of the contrivances carrying the 10 "filling" and passing through the shed, and in its confined sense said term is used to embrace simply the frame carrying the parts operatively connected therewith. Journaled on suitable studs or pins connected with the shuttle-frame are wheels *j*, *j*', *j*''—the former arranged near the outer edge of the frame and adapted to travel on inclined circular track-plates *j*², and the latter arranged at a suitable 15 point inward toward the center of the loom and adapted to travel on inclined track-plates *j*³, said track-plates being secured to and supported by brackets *a*³, attached to the part *a*² of the frame. Journaled on a suitable stud of the shuttle-frame, near the outer rear edge 20 thereof, is a horizontally-arranged wheel, *j*⁴, adapted to roll in contact with and bear against the sides and within the circle described by a series of pins, *j*⁵, closely arranged around the outer edge of track-plate *j*², and on a stud depending from the outer end of an arm, *j*⁶, integrally connected with the shuttle-frame at its 25 outer edge and near its forward end, is another horizontally-arranged wheel, *j*⁷, adapted to roll in contact with the outer sides and with- 30 out the circle of the pins *j*⁵. Extending upwardly and rearwardly from the front face of the shuttle-frame is an arm, *j*⁸, to the free end of which on a stud projecting therefrom is journaled a friction-wheel, *j*⁹, adapted to roll 35 in contact with and be driven by driving-wheel *i*⁹, and in turn to roll in contact with and drive rear wheel, *j*⁹, of the shuttle or shuttle frame or carriage. The force to drive the 40 shuttle being applied near its rear outer corner, there will be a tendency to press the shuttle at this point outward from the center of the machine and the outer forward corner inward; hence the provision of wheels *j*⁴ and *j*⁷, operating on opposite sides of the circle of 45 pins *j*⁵.

*i*¹⁰ represents an arm extending down and curving outward and upward from the bracket *I*, for the purpose of stopping the shuttle from shooting forward out of place and out of control of the shuttle-driver when the latter is 50 stopped. As shown, not only is each individual track-plate inclined, but one is inclined with respect to the other—that is to say, the face of each track-plate is inclined, and the 55 outer, *j*², is placed at a lower horizontal plane than the inner, *j*³. This construction is important, since it enables me to so operate the heddles as to keep both sets of warp-threads in the formation of the shed at all times at the 60 same angle, and consequently under the same tension, and to utilize substantially all of the space in the shed for the shuttle, permitting 65

me to employ a spool or bobbin of larger size than could otherwise be done, as will be understood, and the importance of which will be appreciated by operators of looms of this type. 70

The means just described serve to support and guide the shuttle in its movements when operated by the shuttle-driving mechanism, all as has been so clearly indicated in the explanation of the arrangement and relationship of parts as to need no further description. 75

K indicates the shuttle spool or bobbin on which the weft or filling yarn or thread *W*' is wound, and from which spool or bobbin the 80 weft or filling *W*' is led over a rod or wire, *k*, inward to and through a guide-eye, *k*¹, to and back and forth through eyes or holes formed in a bar, *k*², and beneath the end of a tension-spring secured to said bar, to and through an 85 eye in what I term the "batten-shoe" or "follower," *k*³, curved to conform to the cylindrical form of the weaving-pin, by which batten-shoe the filling is laid and pressed into the fabric somewhat analogous to the manner in 90 which weft is beat up by a reed or lay in an ordinary loom. It is to be noticed, also, that the batten-shoe *k*³ is provided with a guide-eye, *k*⁴, (shown by dotted lines in Fig. 10,) through which eye the weft or filling *W*' 95 passes to its place between the warps on the weaving-pin *d*⁵. This construction serves to assist in guiding and steadyng the weft, so that the batten-shoe will act with certainty thereon, and that it (the weft) will be laid in 100 precisely proper position in the fabric.

To insure the proper opening of the shed for the passage of the shuttle and secure the close insertion of the weft or filling and most effective operation of the batten-shoe, I provide the shuttle on its inner forward part with what I term a "spreader," *L*, formed of sheet metal and **V**-shaped in cross-section, as represented in Fig. 11, and bulged out or forward, as at *l*, a point between track-plate *j*³ 110 and the weaving-pin, as viewed from above, and retreating rearwardly from said point *l*, the inner edge or point, *l*', of said spreader extending to or nearly to the weaving-pin, and being engaged by a forwardly-extending rod 115 or arm, *l*⁶, of the batten-shoe *k*³, which rod *l*⁶ extends around within the spreader and is secured at *l*⁶ to the forward inner portion of the shuttle frame or carrier. This rod *l*⁶ and the brace rods or wires *l*⁷, connected at one end 120 with the rear edge of the spreader *L* and at the other with the supporting-arm *l*⁸ of the batten-shoe *k*³, serve to support the said spreader in proper position in the shed.

As will be supposed, the weft or filling *W*' 125 is laid up in the fabric under heavy tension, in order to secure a closely-woven fabric; and to provide for this tension, in addition to leading the weft in a zigzag course through the eyes in the tension-bar *k*², which in itself would place 130 said weft under considerable stress or strain in drawing it from the bobbin, I pivot a tension plate or spring, *M*, on a stud, *m*, projecting inward from near the rear end of tension-

bar k^2 , and arrange said plate or spring so that its face toward said tension-bar will bear on the weft-yarn threaded therethrough, as shown in Fig. 10. I also provide said tension-bar with a screw-threaded stud, m^1 , which extends through the tension spring or plate M , and has a thumb screw or nut, m^2 , turned thereon, by which means the force by which the tension-spring is made to bear on the weft or filling W' can be adjusted and the tension on said filling regulated.

To secure an even tension on the weft—that is, to compensate for the variation in tension occasioned by the variation in the angle at which the weft is drawn from the bobbin or spool K over the wire k , as the amount of yarn on the shuttle-spool K varies, substantially the same as has been explained with reference to the warp-spoils D —I journal a rod, N , in the shuttle-frame, just forward of or inward beyond the shuttle-spool, and secure thereto an arm, n , provided on the end extending toward the shuttle-spool with a pad, n' , adapted to rest on the spool or bobbin K , and one end of a spiral spring, n^2 , coiled about a stud, n^3 , projecting out from the frame, is secured to a collar, n^4 , attached to rod N , and operates with a tendency to press said pad n' on the yarn on said spool or bobbin K . As the yarn on the spool K is drawn off and said spool becomes empty, the tension of spring n^2 relaxes, and pad n' bears on the yarn on the spool with less force, thus compensating for the increased force or power required to draw the yarn from the spool.

As an addition to the means just described, I may provide, and in most instances prefer to construct, the machine with the form of means represented in Fig. 17—that is, I provide the shuttle-frame on its forward part with a dog, O , pivoted at o to the frame, and adapted to have one arm or end, o' , to bear on the extended core or journal o^2 of the spool or bobbin K , and having its other end or arm, o^3 , engaged by one end of a spring, o^4 , secured to the frame and operating with a tendency to press the arm o' of the dog O on said journal o^2 , and by frictional contact therewith retard its revolution. A cam, o^5 , is secured to the extended end of rod N , and bears upward on said spring o^4 with a tendency to cause the latter to so operate on dog O as to force its arm or end o' with greater force against the journal o^2 of the bobbin or spool K . As the yarn on the spool K is drawn off, and rod N is permitted to turn in the direction of the arrow, Fig. 17, by the operation of spring n^2 , Fig. 10, as also by the pressure of spring o^4 on cam o^5 , said cam will be turned to relieve the stress by which it causes spring o^4 to act on dog O , the form of said cam being such as to permit this operation. Consequently, as the amount of yarn on the spool K decreases, the resistance to the turning of the spool, caused by the frictional contact of arm o' of dog O with its journal or axle, will also decrease.

In the event of the breakage or exhaustion

of a weft or warp thread, I have provided a construction whereby the weaving operations of the machine will be automatically stopped, as I will next proceed to explain.

P represents a bevel-gear secured to the main shaft b^4 at any suitable point, but preferably near or adjacent to driving-pulley b^3 , as seen in Fig. 2. Said wheel P meshes with a like bevel-wheel, p , secured to the upper end of an upright shaft, p' , supported in suitable bearings formed in brackets attached to the frame of the machine, which shaft p' is provided, at a point below wheel p , with another bevel-gear, p^2 , meshing with a similar gear, p^3 , secured on the outer end of a shaft, p^4 , horizontally arranged in the machine and adapted to turn in bearings formed or supported therein. (See Figs. 1, 2, and 18.)

Q represents a disk having an elongated hub, q , coarsely screw-threaded on its interior, and connected by this means with a coarse screw-thread, q' , formed on the shaft p^4 , and frictionally held thereon so as to turn therewith, excepting when opposed with considerable resistant force.

q^2 represents a spiral spring having one end secured to a collar, q^3 , rigidly secured to shaft p^4 , and the other end attached to the inner end of hub q , which latter has a groove, q^4 , formed around its entire circumference, all as clearly shown in Figs. 18 and 19. Projecting horizontally outward from the outer face of disk Q are pins q^5 , adapted to engage the pins r , arranged vertically in a hoop or ring, R , horizontally arranged in the machine, and supported on pulleys r' , which latter devices are arranged so as to turn on studs r^2 , secured in the brackets a^5 of the frame.

The construction and arrangement of the parts last described hereinbefore are such that as shaft p' is revolved it will, through the medium of gears $p^2 p^3$, revolve shaft p^4 , and with it disk Q , held by frictional contact and by the stress of spring q^2 to turn in unison therewith, and the pins q^5 of disk Q , engaging pins r of hoop or ring R , will turn the latter on pulleys r' , when, as has been said, no considerable resistance is offered to the turning of disk Q . Should, however, obstruction be offered to hold hoop R from being revolved, the revolution of disk Q will also be stopped, though shaft p^4 will continue to revolve, the result of which will be to screw disk Q and its collar q back on said shaft p^4 , so as to disengage pins q^5 from pins r , and when said rim R is again permitted to revolve the tension of spring q^2 will operate to screw said disk Q and its attached hub back to its former and normal position, so as to bring pins q^5 and r into engagement with each other, all as will be clearly understood by those skilled in the art upon an inspection of the figures of the drawings last hereinbefore mentioned.

S represents a lever pivoted, at s , at a suitable point on the bracket a^5 , provided at its upper end with a pin or anti-friction roller journaled on a stud or pin and extending into

the groove g^4 of the elongated hub of disk Q, Fig. 18, and resting against or loosely connected with a short laterally-extending arm, s^5 , of a latch-lever, s^2 , pivoted to the frame at s^3 , and having a spring, s^4 , connected therewith and with the frame at a suitable point outward from its fulcrum, which spring s^4 operates with a tendency to throw the end s^5 of said lever in the direction of the arrows pictured in Figs. 20 and 21. The outer end, s^6 , of said lever is supported in a suitable loop or guideway, s^7 , and is adapted to be engaged and operated against the tension of spring s^4 by the operator.

- 15 The inner end of lever s^2 is provided with a hook or notch, s^8 , adapted to engage or hook over the upper end of a shipper-lever, T, pivoted or fulcrumed at t to a projection or ear on the bracket b of the frame, and guided at 20 its upper end in a loop or way, t' , while at its lower end it is connected to the bow portion of a U-shaped rod (see Fig. 22) having the inner ends of its arms t^1 t^2 connected to a yoke, t^3 , having a stud, t^4 , extending into a groove 25 formed in the outer circumference of the clutch part t^5 , having a feather-and-groove connection with the driving-shaft B—that is, splined thereon so as to turn therewith, and at the same time be longitudinally movable thereon. 30 Said clutch part t^5 is adapted to engage with the clutch part t^6 , constituting a portion of the hub of pulley b^2 , which is loose to turn on shaft B when not in engagement with the clutch part t^5 . Arms t^2 of the U-shaped rod 35 are guided in suitable ways formed in the bracket b , and spiral springs t^7 , surrounding said arms and arranged between one of their bearings and fixed collars t^8 thereon, operate with a tendency to draw the U-shaped rod and 40 clutch part t^5 , with which it is connected, away from clutch part t^6 , so as to leave pulley b^2 to turn freely on shaft B without revolving the same. It will now be understood that if the upper end of lever T were moved inward 45 in the direction of the arrow, Fig. 18, its lower end would be moved in the reverse direction or opposite to the stress or force exerted by spring t^7 forcing clutch part t^5 into engagement with clutch part t^6 , causing pulley b^2 to be turned with driving-shaft B and putting the machine into operation. At the same time the upper end of said lever T would be caught behind the hook s^8 of lever s^2 and be held in that position, as represented in 50 Fig. 20. Should, however, lever s^2 be moved to the position represented in Fig. 21, either by operating said lever by hand or automatically through the medium of lever S, as herein-after explained, springs t^7 , acting on the U-shaped rod, will disengage clutch part t^5 from clutch part t^6 , leaving pulley b^2 to turn with freedom on shaft B and the machine to stop.

As before explained, each warp-thread is led from the tension device through an eye 65 formed in the inner end of a feeler-pin, d^3 , which latter device is arranged so as to slide in bearings formed in a small bracket, V, secured

to the lower face of a ring, v, resting on and secured to the upper ends of brackets a^5 . Attached by one end to said feeler-pin d^3 at a point between its bearings, and having its other end resting against one of said bearings, is a spiral spring, v , operating with a tendency to press said feeler-pin outward, as indicated by the arrow, Fig. 6, so that its outer end will 75 engage with the vertical pins r of ring or hoop R and stop its revolution, as also the revolution of disk Q, which will effect the screwing inward of said disk and its attached hub and operate lever S, all as hereinbefore explained, 80 to unlatch shipper-lever T and stop the machine. The tension on warps W is insufficient, however, to hold said feeler-pins inward out of engagement with the pins r of rim or hoop R, so that the machine may operate so long as 85 the warps remain intact and be stopped through the instrumentality of said feeler-pins d^3 when a warp breaks or runs out.

Another function of the feeler-pins is to take up the slack in the warps as the heddles operate to change the position of the warps to form the shed, their outer ends being far enough distant from the pins r to permit them to move for this latter purpose without engaging or coming in contact with said pins. By 95 this construction, also, the feeler-pins operate to take up any undue slackness of individual warps caused by uneven winding of the same on the warp-spools, and for the same reasons as those explained should any individual warp 100 become very slack its feeler-pin will operate to stop the machine in the same manner as though such warp had been broken.

To effect a stoppage of the loom automatically when a weft or filling thread, W', breaks, 105 I provide the mechanism which will next be described.

X represents a rod (see Fig. 1) supported horizontally in bearings formed in the bracket a^5 and part a^2 of the frame in such position 110 with respect to ring or hoop R as to be moved outward into engagement with or inward to be disengaged from pins r . A spiral spring, x, surrounding said rod X and operating between a collar, x' , fixed thereto and the side of the 115 frame, tends to press said rod outward, as aforesaid. A spring-actuated latch, x^2 , Fig. 24, is pivoted to the inner face of the frame a^2 , and is adapted to snap into a notch formed in the inner end of rod X, and so hold the same from 120 engagement with pins r , as aforesaid.

As shown in Fig. 10, tension-bar k^2 is pivoted at its rear end, as at x^3 , to lugs formed on the shuttle-frame, and at its forward end it is loosely connected to the inner end of a rod, x^4 , suitably mounted in bearings, so as to slide therein and through the hollow axle x^{11} of the forward wheel, j. The construction and relationship of the parts just described are such that the tension on the weft-yarn as it is drawn from 125 the shuttle will hold the forward end of bar k^2 inward, and consequently maintain rod x^4 in the same position as represented in Fig. 10; but should said weft-thread break, spring x^5 ,

operating on rod z^4 , will move said rod outward, so that its outer end will in its movement come in contact with the free end of latch and move it so as to unlock it from rod 5 X, and permit spring x to move the latter into engagement with the pins r of ring or hoop R, and by said ring through the medium of its adjuncts, as before explained, operate the shipper-lever to stop the machine.

10 The construction and operation of the mechanism for taking up or drawing the fabric from the weaving-pin d^5 , which is preferably formed as an integral part of the collar h^2 , will next be explained.

15 Y represents a worm formed on the lower end of vertical shaft p' , intermeshing with a worm-gear, y , secured to the outer end of a horizontal shaft, y' , provided on its inner end with a gear, y^2 , driving, through the medium of 20 idle-gear y^3 , a large toothed gear, y^4 , on a shaft, y^5 , having its bearings, as have also wheels y^6 , in a frame, Z, located directly underneath weaving-pin d^5 . On the end shaft, y^5 , opposite that at which wheel y^6 is secured, is a toothed 25 pinion, y^6 , gearing with another toothed pinion, y^7 , on a shaft, y^8 , parallel with and in the same horizontal line with shaft y^5 , so that as shaft y' is revolved by the operation of worm Y and worm-gear y the train of gears y^3 , y^4 , y^5 , 30 and y^7 will be revolved. Journaled in the upper end of an upwardly-extending arm, z , of frame Z on a shaft, z' , is a drum or roller, z^2 , while directly below said drum or roller is another, z^3 , journaled on a shaft, z^4 , and underneath the latter drum or roller z^3 are two 35 devices of similar character, one of them being hidden by other parts affixed to shafts y^5 y^8 , with their peripheries rolling in contact with each other, and farther down and on a 40 shaft journaled in one side of the frame is a guiding roller or drum, z^5 . The surfaces of the rollers z^2 z^3 may be roughened or otherwise frictioned, while the peripheries of the rollers affixed on shafts y^5 y^8 may be covered 45 with any suitable yielding material.

As the fabric is woven around weaving-pin d^5 it passes down between rollers z^2 z^3 , by which it is flattened, as shown in Fig. 25, keeping the fabric from being twisted or turned on 50 the weaving-pin, as the tendency would be. From rollers z^3 the fabric passes between the rollers on shafts y^5 y^8 , which exert sufficient draft thereon to draw it off the weaving-pin, which draft, since the fabric is woven with 55 great tension around the pin, is very considerable. Roller z^5 is simply a guide-roller over which the fabric passes after being drawn off, as before described.

To permit the rollers or drums on shafts y^5 60 y^8 to be operated by hand to draw off or take up the fabric, I pivot a shipper-lever, z^6 , to the frame Z, and connect it above its fulcrum-point with a clutch part, z^7 , formed on the hub of wheel y^4 , said wheel being splined on shaft 65 y^5 so as to be moved longitudinally thereon a sufficient distance to disengage it from clutch part z^8 , rigidly affixed to said shaft. Arms z^9

are affixed to clutch part z^8 to permit the latter and shaft y^5 to be revolved when disconnected from clutch part z^7 , as aforesaid. Spring 70 z^{10} operates between a collar on the end of shaft y^5 and the hub of wheel y^4 to move the latter and its attached clutch part z^7 into engagement with clutch part z^8 when the operator releases his hold on lever z^6 .

75 The operation of the loom has been so far set forth in the description of its construction and the relationship and operation of its various parts as to leave little or nothing more to be explained. It is to be noticed, however, 80 that as the loom is here represented it is organized to be operated with two shuttles, and appliances connected with each for laying its weft-thread up into the fabric, one shuttle being arranged substantially at the point where 85 the slide-blocks e^3 are moved farthest toward the periphery of the spider-plate, and the other at the point where said slide-blocks are drawn back to their innermost limit in the opposite direction. These points of arrangement of the shuttles are those at which the shed is opened to its utmost limit, and the points therebetween are those at which the two sets of warp change position by the operation 90 of the heddles, as hereinbefore explained. 95

The sleeve c^3 and weaving-pin d^5 are made hollow, so that the rubber lining for the hose or other analogous article woven on the machine, or a wire, rope, or cable to be covered, or any other article around which it is desired 100 to weave a fabric or cover, may be fed through said sleeve and weaving-pin and drawn off, leaving the latter as substantially woven about the former.

Though some of the devices or groups of devices have been described as though but a single set or series are employed in the loom, it will be understood that as many series or sets are used as are necessary to carry on the operation of weaving.

105 Having thus described my invention, what I claim is—

1. The frame, a stationary spider-plate, E, provided with radial grooves e^2 , supported by the frame, slides e^3 , for operating the heddles, 115 arranged in the grooves of the spider-plate, and an inverted rotary cam, e^6 , adapted to engage said slides to reciprocate them in the grooves of the spider-plate and at the same time positively hold them therein, substantially as set forth.

2. The frame, a rotary main shaft, a spider-plate, E, provided with radial grooves e^2 , supported by the frame, a stationary sleeve, also supported by the frame, a sleeve surrounding 125 and adapted to turn on said stationary sleeve, a gear secured to said revoluble sleeve, a gear on the main shaft intermeshing with said first-mentioned gear, slides e^3 , for operating the heddles, arranged in the radial grooves e^2 of the 130 spider-plate, and an inverted cam, e^6 , secured to and adapted to be rotated by said revoluble sleeve, and engaging with said slides, to operate them and at the same time positively hold

- them in their grooves, substantially as set forth.
3. The frame, the radially-grooved stationary spider-plate supported thereby, the slides adapted to operate in said grooves, a rotary cam engaging and operating said slides, rock-shafts having bearings in the frame, arms secured to said rock-shafts, other arms connecting the slides with the first-mentioned arms, 10 rocker-arms f^3 , also secured to the rock-shafts, the heddle-bars supported and guided in the frame, and rods connecting the heddle-bars with said rocker-arms, all arranged, combined, and operating substantially as and for the purposes hereinbefore set forth.
4. The frame, radially-grooved stationary spider-plate supported thereby, the slides adapted to operate in said grooves, a rotary cam engaging and operating said slides, rock-shafts having bearings in the frame, arms F^f , rods f^4 , the heddle-bars and heddles, collars f^5 , forming a part of the heddle-bars, and rods f^6 , forming guides for the heddle-bars, all combined and operating as and for the purpose hereinbefore set forth.
5. The warp-spool, an adjustable guide and tension bar, d^1 , provided with eyes d^2 , through which the yarn may be passed, a revoluble tension-drum, around which the yarn may be passed, and means, substantially as described, for retarding the revolution of said tension-drum and for adjusting such retarding means to permit the drum to turn with greater or less ease, all combined, arranged, and operating as and for the purpose hereinbefore described.
6. The frame, a warp-spool, an adjustable guide and tension bar, d^1 , provided with guide-eyes, through which the yarn may be passed, a revoluble tension-drum, around which the 40 yarn may be passed, a band-wheel secured to said drum, a band wound around said wheel and having one end secured to the frame, rod g^7 , to which the other end of said band is secured, and adjusting-nut g^8 , screwed upon the other end of said rod, combined and operating as and for the purposes hereinbefore set forth.
7. The warp-spool, arm G , provided with pad g^9 , rod g^9 , nut g^9 , spring g^9 , guide and tension bar d^1 , tension-drum d^2 , band-wheel g^4 , band g^5 , rod g^7 , and nut g^8 , combined and operating as and for the purposes described.
8. The frame, a stationary gear, h^1 , supported thereby, a revoluble sleeve supported by the frame, a ring or collar, h^2 , rigidly secured to said revoluble sleeve, a shuttle-driver frame secured to said ring or collar and extending radially from near the center of the machine, a shaft having bearings adapted to turn in said shuttle-driver frame, a gear fixed 55 to one end of said shaft and intermeshing with said stationary gear, and a shuttle driving wheel geared with said shaft, all combined and operating as and for the purpose set forth.
9. The fixed gear, a revoluble ring or collar, the shuttle-driving frame secured to and operated by said ring or collar, a shaft adapted to turn in said frame, a gear on one end of
- said shaft intermeshing with said fixed gear, gear i^2 , a shaft, i^4 , gear i^5 , and driving-wheel i^6 , all arranged, combined, and operating as hereinbefore set forth.
10. The frame provided with circular tracks j^2 j^3 , adapted to support the shuttle on one side of the shed in the warps, a shuttle-frame provided with wheels adapted to support it and to travel upon said tracks, an arm, j^8 , attached by one end to said shuttle-frame, an idler wheel, j^9 , carried on the free end of said arm and adapted to engage one of the wheels of said shuttle frame and drive the latter, a shuttle-driver frame revoluble in the line of said circular tracks, a wheel, i^6 , journaled in said shuttle-driving frame and adapted to engage said idler, and means for rotating said wheel i^6 , combined and operating as and for the purposes set forth.
11. The frame provided with circular tracks, a shuttle-frame provided with wheels adapted to support it and to travel upon said tracks, a series of pins arranged circularly in the frame, a wheel horizontally arranged on the outward rearward part of said shuttle-frame and adapted to roll on the sides of the pins within the circle thereof, a wheel horizontally arranged on the outer forward part of the shuttle-frame and adapted to roll on the sides of the pins without the circle thereof, a wheel rearward of the series supporting the shuttle-frame to drive the same, and means for rotating said wheel, all combined, arranged, and operating as and for the purpose hereinbefore set forth.
12. The frame provided with circular tracks j^2 j^3 , adapted to support the shuttle on one side of the shed in the warps, one track being arranged at a lower horizontal plane than the other, the horizontally-arranged shuttle provided with wheels adapted to travel on said tracks, the heddles and their operating mechanism, and means to drive the shuttle, all arranged, combined, and operating as and for the purposes hereinbefore set forth.
13. The frame provided with the circular tracks j^2 and j^3 , one being arranged at a lower horizontal plane than the other, constructed substantially as hereinbefore set forth.
14. The frame provided with the circular inclined tracks j^2 j^3 , one track, j^2 , being placed at a lower horizontal plane than the other, j^3 , as set forth.
15. The frame, the weaving-pin, heddles to control the warps, means for operating the heddles, the shuttle and mechanism to support and drive it, a spreader, L , V-shaped in cross-section, as shown, connected with the shuttle to insure the opening of the shed for the passage of the shuttle, tension mechanism connected with the shuttle, arm l^5 , connected with the shuttle and provided at its inner end with the curved batten-shoe k^3 , through which the filling-thread is adapted to pass, and by which it is adapted to be pressed between the warps supported on the weaving-pin, and arm l^7 , supporting the spreader and connected with the batten-shoe to brace the latter, all com-

bined, arranged, and operating as and for the purposes set forth.

16. The shed-spreader L, formed of sheet metal, V-shaped in cross-section, as shown, and bulged out or forward at l, rod or arm l², extending around within the spreader, and the shuttle-frame, combined and operating substantially as set forth.

17. The shuttle-frame, supporting-arm l³, batten-shoe l⁴, shed-spreader L, formed of sheet metal and V-shaped in cross-section, as shown, and bulged out or forward at l, and retreating rearwardly from said point l, rod or arm l², extending around within the spreader, and brace rods or wires l⁴, combined and operating substantially as set forth.

18. The shuttle-frame provided with the rod k and guide-eye k², the shuttle-spool bar k³, provided with a plurality of guide-eyes, through which the yarn from the spool may be led back and forth, a tension-plate pivoted by one end to said bar, stud m¹, and thumb-nut m², combined, arranged, and operating as and for the purposes hereinbefore set forth.

19. The shuttle-frame, the shuttle-spool, its journals, dog O, pivoted to the frame and having one of its arms bearing on one of the journals of the spool, cam o⁵, spring o⁴, rod N, arm n, spring n², and pad n¹, all combined and operating as and for the purposes described.

20. The frame, ring v, bracket V, feeler-pins d¹, and spring v², all combined, arranged, and operating as and for the purposes hereinbefore set forth.

21. The feeler-pins, supports therefor, spring v¹, hoop R, provided with pins r, revolving shaft p¹, disk Q, provided with pins q⁵, engaging with said pins r, said disk having a screw-threaded connection with said shaft, spring q², lever S, and belt-slipping mechanism, substantially as explained, connected with said lever, all combined and operating substantially as and for the purposes hereinbefore set forth.

22. Hoop R, provided with the pins r, pulleys r¹, for supporting said hoop, revoluble shaft p¹, and disk Q, provided with pins q⁵, and having a screw-threaded connection with said shaft, whereby when the movement of hoop R is stopped movement of said disk along the shaft will be occasioned, as and for the purposes set forth.

23. The shuttle-frame, tension-bar k², pivoted by one end to said frame, rod x⁴, loosely connected with the other end of said bar, spring x⁵, latch x², rod X, spring x, hoop R, provided with the pins r, revoluble shaft p¹, disk Q, provided with pins q⁵, and having a screw-threaded connection with said shaft, spring q², lever S, and belt-slipping mechanism, substantially as explained, connected with said lever.

24. The driving-shaft, a pulley loosely mounted thereon, provided with the clutch part t⁶, clutch part t⁵, splined on the shaft to turn therewith, but longitudinally movable thereon; the U-shaped rod connected with clutch part t⁶, springs t¹, lever T, latch-lever s², provided with the laterally-extending arm s³, lever S, and mechanism, as set forth, for operating said latter lever, all combined, arranged, and operating as and for the purposes hereinbefore described.

25. The main shaft, gears P p, shaft p¹, worm Y, shaft y¹, gears y y² y³ y⁴, shafts y⁵ y⁶, drums on said shafts, and gears y⁶ y⁷, combined, arranged, and operating as and for the purposes set forth.

26. Frame Z, shafts y⁵ y⁶, drums on said shafts, gears y⁶ y⁷, gear-wheel y⁴, provided with a clutch part and splined on shaft y⁵ to move longitudinally thereon, but to turn therewith, shipper-lever z⁶, connected with said gear to move the same longitudinally on its shaft, another clutch part rigidly connected with said shaft to turn therewith, arms connected with said latter clutch part to turn the same, and mechanism, as set forth, to turn said wheel y⁴, all constructed, arranged, combined, and operating as and for the purposes described.

27. Frame Z, guiding-drum z⁵, shafts y⁵ y⁶, drums thereon, gear-wheels y⁶ y⁷ y⁴, means for revolving the last-mentioned gear, arm z of frame Z, and drums or rollers z² z³, journaled in the upper end of said arm, combined and operating as and for the purposes described.

In testimony whereof I have signed my name to this specification, in the presence of two subscribing witnesses, this 16th day of September, A. D. 1886.

ALBERT DE LASKI.

Witnesses:

ARTHUR W. CROSSLEY,
A. D. HARRISON.
